UNITED STATES PATENT OFFICE.

GEORGE W. HAWLEY, OF BRIDGEPORT, CONNECTICUT, ASSIGNOR TO THE KNY-SCHERER CORPORATION, A CORPORATION OF NEW YORK.

ADJUSTABLE SPRING-TRACTOR.

1,363,114.

Specification of Letters Patent. Patented Dec. 21, 1920.

Application filed January 22, 1920. Serial No. 353,220.

To all whom it may concern:

Be it known that I, GEORGE W. HAWLEY, a citizen of the United States, and a resident of the city of Bridgeport, State of Connecticut, cut, have invented certain new and useful Improvements in Adjustable Spring-Tractors, set forth in the following specification.

This invention relates to surgical apparatus of the type for applying limb traction. In the reduction of many bone fractures success is dependent upon relieving the reduced fracture of all muscle tension. It is not unusual that each individual case require an individually calculated or measured amount of traction for the best results. As the traction applied to a limb is primarily to overcome muscle and tissue resistance, any relaxation in the muscle resistance necessitates an adjustment of the tractor apparatus. Heretofore it has been usual to apply the traction through the medium of taut bandages exerting tension through some framework or through the medium of weights and pulleys. In the case of bandages, while the tension applied at the first dressing may be correct, changed conditions result frequently in the need of many readjustments which with bandages are difficult and time taking. In the case of weights and pulleys, the requirement of a fixed positioning of the patient is a disadvantage and likewise the apparatus, necessarily extending out of the patient's bed, also has disadvantages.

An object of the present invention is to provide for the ready adjustment of tractor means to supply a measured tension to a limb. It is also an object of the invention to combine such means with a frame or splint approximately coextensive with the limb under treatment.

Further objects are to improve in general adjustable traction apparatus for limb extension. The above will better be understood by reference to the illustrative embodiment described in the following specification, which should be read in connection with the accompanying drawings forming a part hereof. The claims are directed to this illustrative embodiment solely for purposes of illustration and not limitation.

In the drawings—

Figure 1 is a diagrammatic view illustrating the relative positioning of the frame to a leg;

Fig. 2 is a perspective view showing the apparatus exerting measured traction upon a leg extremity;

Fig. 3 is a plan view, with parts broken away and with parts shown in section, of the traction mechanism; and

Fig. 4 is a vertical section, with parts shown in elevation and with parts omitted, through line IV—IV of Fig. 3.

In the embodiment illustrated the extensor frame A comprises one or more, preferably a pair of, extensor struts 1 and 2 adapted to extend along the limb to be treated and of any suitable shape and material to resist the traction to be applied to the limb. In the embodiment shown the struts are in the form of steel rods having a pocketed tension resisting part or cross bar 3 at their extreme ends, and preferably formed integral therewith. The body ends of the frame A are secured to an inclined ring 4 which may have a surface padding 5 for direct engagement with the body.

A cross-head B is provided with a side bearing 6 coöperating with the strut 2 and a symmetrical bearing 7 coöperating with the strut 1, these bearings being provided at the ends of arms 8 and 9. The cross-head B also has a boss 10 to provide for the attachment of the adjustable traction mechanism. The arms 8 and 9 are provisions for attaching tension bandages when the same are employed as surgical connectors. The cross-head likewise is preferably provided with hook shaped clips 12 and 13 which form a seat transverse to the struts 1 and 2 and are shown seating the cross pin 14, which connects the stirrup structure 16 and 17. In this form the stirrup structure provides in each leg an eye 18 for leg 16 and an eye 19 for leg 17, and also fingers 20 and 21 for the respective legs. These eyes and fingers serve to mount and support a foot support C, preferably formed of bent wire, as shown, and carrying the hammock 22 against which the ball of the foot D rests. The uprights 23 and 24 of the foot support have rearward extensions 25 and 26 terminating in the toe loop 27, and at their opposite ends in feet 29 and 30, which coöperate with the eyes and offsets of the stirrup. Stirrup links are formed with hooks 40 to hook over the pin 41 which, in the embodiment illustrated is in direct surgical engagement with the os calcis 42 of the foot D.

The adjustable traction mechanism E operates as an adjustable traction measuring connector between the cross-head B and the tension resisting part of bar 3. A buckle or 5 removable clip 43 directly engages the bar 3 and has secured to it a nut-like part 44 (in the embodiment shown this is an integral part of the buckle 43 in a single casting). An axially extensive sleeve 45 has surface 10 threads 46 mating with the threads of the nut or block 44, and is provided with an axial bore 47 terminating at its free end in a stop 48 cast as an integral inturned flange with the sleeve 45. The opposite end of the 15 sleeve 45 is threaded into the finger cap 49 in which it may be irremovably secured if desired as by solder 50. A stem 51 is secured as by riveting 52 centrally of the cross-head B, and extends loosely through the bore 53 20 of the stop 48 and axially internally of the bore 47. This stem is preferably provided with a graduated or measuring scale 54, indicating pounds pull. A swiveling stop in the form of an enlargement or washer 55 is 25 swiveled to the far end of the stem 51 as by the riveting 56. Between the stops 55 and 48 a compression spring 57 is located to resist the outward movement of the stem 51 and so that a measured traction on the cross-head B is indicated by the scale 54, read 30 against the end of stop 48.

Although the actual construction of the traction mechanism as embodied has been described, it is to be understood that the 35 claims are drawn to cover any obvious interchanges and modifications in the combination of the relatively threaded parts and the stem and their connections between the cross-head B and the buckle 43. For example, it is conceivable that the sleeve be 40 threaded into the cross head instead of into a part connected with the buckle, or that the stem could be threaded and the spring be between the sleeve and the buckle or between the sleeve and the cross-head. 45

It should also be understood that whereas a tractor frame comprising two struts has been illustrated and described, it is contemplated that the omission of either strut 50 would still provide a frame measurably serviceable, and that this is contemplated in the claims. Likewise the cross-head, which in its present embodiment has a slide bearing upon each strut, would still be a cross-head 55 if providing a bearing solely upon one strut.

What is claimed and desired to be secured by United States Letters Patent is:—

1. In limb traction apparatus, an extensor-frame having one or more extensor-struts 60 with a transverse tension resisting bar at one end; in combination with an adjustable tractor mechanism for exerting traction on a limb through the medium of a surgical connector, comprising a buckle removably 65 securable to said resisting bar having a trac-

tion functioning part offset from the plane of said resisting bar and strut and a hook-part to engage said resisting bar, a cross-head having provisions for attaching the free end of said surgical connector and one or 70 more end guide bearings for laterally removably engaging against said one or more struts, and mutually threaded mating parts adjustably linking said buckle with said cross-head, but capable as a whole of ready 75 removal from said frame.

2. In limb traction apparatus, an extensor-frame having a pair of extensor-struts and a transverse tension resisting bar cross-connecting said struts; a cross-head having open 80 guides for slidably engaging said struts, provisions for attaching surgical connectors, and a central boss offset below the plane of said struts; a buckle removably securable to said resisting bar and having a socket offset from the plane of said struts and alined with said boss; and a measuring traction link comprising a threaded shank adjustable upon rotation combined with a spring scales alined with and adjustably linking 90 together said boss and said socket.

3. A surgical tractor mechanism for applying an adjustable measured traction to a limb, comprising a connector securing cross-head; a tension resisting part; and 95 adjustable spring means for exerting traction between said tension resisting part and said cross-head, said means comprising an internally threaded buckle for attachment to said resisting part, an externally threaded 100 sleeve screwed into said buckle and having an axial bore, a stem connected at one end to said cross-head and extending into the bore of said sleeve, and a compression spring within said bore and resisting the 105 withdrawal of said stem from said bore.

4. In surgical traction apparatus for exerting traction on a limb, an extensor frame comprising a pair of extensor-struts adapted to extend along the limb, an inclined ring 110 for embracing the body end of the limb, and a tension resisting bar cross-connecting the free ends of said struts in combination with means for applying a measured adjustable traction upon a limb, said means 115 comprising a buckle detachably connectable with said tension resisting bar; a cross-head having end guides engaging said struts to prevent rotation of said cross-head but permitting a sliding movement thereof along 120 said struts, said cross-head having provisions for the attachment of surgical connectors, an externally threaded sleeve having an axial bore, a part secured to said buckle forming a threaded end for said sleeve; a stem secured to said cross-head and extending into the bore of said sleeve; a stop at the end of said bore and at the end of said stem; and a compression spring reacting 125 against said stops.

5. In surgical traction apparatus for exerting traction on a limb, an extensor frame comprising a pair of extensor-struts adapted to extend along the limb, an inclined ring
5 for embracing the body end of the limb, and a tension resisting bar cross-connecting the free ends of said struts in combination with means for applying a measured adjustable traction upon a limb, said means comprising
10 a buckle detachably connectable with said tension resisting bar; a cross-head having end guides engaging said struts to prevent rotation of said cross-head but permitting a sliding movement thereof along said struts,
15 said cross-head having provisions for the attachment of surgical connectors comprising hook-like clips forming a seat transverse to said struts, an externally threaded sleeve having an axial bore, a part secured to said buckle forming a threaded end for said 20 sleeve; a stem secured to said cross-head and extending into the bore of said sleeve; a stop at the end of said bore and at the end of said stem; and a compression spring reacting against said stops. 25

In witness whereof I have signed my name to this specification, this 3rd day of December, 1919.

GEORGE W. HAWLEY.
